UNITED STATES PATENT OFFICE.

DANIEL A. LOESER, OF SAG HARBOR, NEW YORK.

DESIGN FOR A BACK FOR BRUSHES OR SIMILAR ARTICLES.

SPECIFICATION forming part of Design No. 27,855, dated November 16, 1897.

Application filed October 5, 1897. Serial No. 654,186. Term of patent 7 years.

To all whom it may concern:

Be it known that I, DANIEL A. LOESER, a subject of the Emperor of Germany, residing at Sag Harbor, in the county of Suffolk and 5 State of New York, have invented and produced a new and original Design for Backs for Brushes, Mirrors, or Similar Articles, of which the following is a specification, reference being had to the accompanying drawing, which 10 shows the back of a brush or mirror having my design applied thereto.

The leading or characteristic feature of my design consists of a series of ribs on the outer edge of the back, increasing in size toward 15 the handle, and wreaths of flowers partially surrounding a plain central field and separated from said ribs by raised ribs which at the outer end of the back merge into a fanciful scroll and at the opposite end into a 20 bouquet of flowers, the handle being decorated in harmony with the back, as shown.

Referring to the drawing, A represents the

back for a brush or mirror, and B the handle. Near the outer edge of the back are ribs C, increasing in size toward the handle and merging in the scrolls D. 25

E represents wreaths of flowers, partially surrounding the plain central portion F and separated from the ribs C by the lines or ribs G, the latter ending in the scrolls H at one 30 end of the back and in the bouquet of flowers I at the opposite end.

The handle B is decorated in harmony with the back, being provided with the ribs J at the sides and with the foliated scrolls K at 35 the end.

What I claim is—

The design for the back for a brush, mirror, or similar article, substantially as described.

DANIEL A. LOESER.
